COMBINED SHOE POLISH BOTTLE HOLDER AND TRAY

Irving J. Bottner, New York, N.Y., assignor to Knomark,
Inc., Brooklyn, N.Y., a corporation of New York

Filed July 28, 1960, Ser. No. 61,551

Term of patent 7 years

(Cl. D58—26)

FIG. 1

FIG. 4.

FIG. 1 is a top plan view of a combined shoe polish bottle holder and tray, embodying my new design;

FIG. 2 is a bottom plan view thereof;

FIG. 3 is a sectional view taken on line 3—3, of FIG. 1; and

FIG. 4 is a top perspective view thereof.

I claim:

The ornamental design for a combined shoe polish bottle holder and tray, as shown.
